PULSATATOR FOR MILKING MACHINES

Erik August Forsberg, Nockeby, Sweden, assignor
to Aktiebolaget Separator, Stockholm, Sweden,
a corporation of Sweden

Application June 11, 1942, Serial No. 446,636
In Sweden September 24, 1941

12 Claims. (Cl. 31—61)

For efficient operation of many pneumatically driven devices, of which milking machines are an important class, it is important that the rate of pulsation, when once correctly adjusted, should be uniform.

An outstanding difficulty with many such devices is that the throttle valves, usually adjustable, by which the pulsation rate is regulated, and which must necessarily have quite small openings, are liable to be clogged by dust, etc., which, of course, alters the pulsation rate.

In order to avoid this clogging and resultant changes of speed, it has been suggested that the operating fluid be left unthrottled and the speed be regulated by throttling the flow, between two containers, of a small quantity of suitable fluid completely separated from the surroundings and thus protected from entrance of impurities. One device using this principle is described in U. S. Patent No. 1,750,634, issued to E. A. Forsberg on March 18, 1930.

The present invention employs the same principle for control but differs substantially therefrom in its mechanical construction.

In the accompanying drawings, which illustrate embodiments of my invention:

Figure 1 is a longitudinal section showing the construction of a preferred form of pulsator.

Figure 2 is a partial section of an alternative form of motor member adapted for use with the same control and valve members shown in Fig. 1.

Figure 3 is a similar partial section showing another form of motor member.

The pulsator is adapted for operation by the difference between two pneumatic pressures, the higher being atmospheric and the lower, usually about half of atmospheric, hereinafter referred to as "vacuum."

Referring to Fig. 1: A is a passage providing constant communication between the vacuum and the chamber B at the center of a double valve C through which a rod I has a limited longitudinal movement. The chamber D at the left, and chambers E and G at the right, of valve C are connected by passages D' and G' with the surrounding atmosphere. The left head of double valve C, in its movement to left and right in chamber P, contacts alternately with a smaller valve seat adjacent chamber D and a larger seat adjacent chamber B, while the right head, in chamber N, contacts alternately with a larger seat adjacent chamber B and a smaller seat adjacent chamber E.

A bellows H, inside chamber G, is compressed and elongated by movement of rod I and in its

movement forces air through port T to chamber U or draws air from chamber U; said chamber being always at atmospheric pressure but closed from the surrounding air and dust by the loose flexible diaphragm V.

Attached to the left end of rod I, reciprocable in chamber D and separating it from chamber L, is a small piston head F rigidly attached to a larger piston head K reciprocable in chamber L and separating it from chamber M. A desirable ratio for the dimensions of pistons K and F is such that the diameter of the former is the square root of two times that of the latter.

Chamber L is connected, through port A', with vacuum passage A. Chamber M is connected through a port R' with a passage R. Passage R communicates at one end with chamber N and at its other end is adapted for connection with one pair of teat cups. Passage S communicates at one end with chamber P and at its other end is adapted for connection with another pair of teat cups.

The construction shown in Fig. 2 and its operation are similar to that of Fig. 1 except that large and small diaphragms K' and F' are substituted for the large and small pistons K and F of Fig. 1. The chambers corresponding to chambers M and L of Fig. 1 are lettered M' and L'.

The construction shown in Fig. 3 differs from that shown in Fig. 1 in that a continuous force toward the right is obtained by a spring W instead of by providing a vacuum between differential pistons. The chambers on opposite ends of the piston F² are marked M² and D².

The operation of the pulsator shown in Fig. 1 will be explained.

Assuming that the moving element has completed its stroke to the left and the bellows H is full of air at atmospheric pressure: Air can flow through passage G' and chambers G and E to chamber N where it presses the right hand end of the double valve C toward the left because its other side is exposed to the vacuum of large diameter chamber B. This force is opposed by atmospheric pressure from chamber D but because this chamber is smaller the net force is toward the left.

Air also flows from chamber N, through passages R and R', to chamber M. With atmospheric pressure on the left end and vacuum on the right end of large piston K the force toward the right is much greater than that toward the left from smaller piston F with atmospheric pressure on its right end and vacuum on its left end. The pistons and the rod I begin to move

toward the right and continue to so move, as fast as they can force air out of bellows H through port T, until the boss a on piston F contacts the left end b of the double valve C. Here they pause until flow of air out of the bellows H reduces its resistance to movement toward the right below the difference between the force toward the right, from piston K and that toward the left from valve C, wherefore valve C starts toward the right. As soon as the right head of valve C leaves its seat, its resistance to movement toward the right ceases and the stroke of the valve and the rod I with its attached pistons and bellows toward the right is quickly completed.

Chamber M is now connected, through passages R' and R, chambers N and B and passage A with vacuum. Because there is vacuum on both sides of piston K it has no force in either direction, but piston F, with atmospheric pressure at its right end and vacuum at its left, has a strong force toward the left and, through rod I, expands bellows H, as fast as air can flow in through port T, until the boss adjacent the bellows contacts the right end of double valve C. It will then pause, as it did in the movement toward the right, until the resistance of the bellows becomes less than the difference between the leftward force of piston F and resistance to movement of valve C, which is now a force toward the right, when the valve and other parts will quickly complete their stroke and conditions will be those at the start.

The operation of the motor members shown in Fig. 2 is the same as that of those shown in Fig. 1.

In the motor shown in Fig. 3, with parts in the position shown, there is atmospheric pressure against both ends of piston F² and the spring W will move it toward the right as fast as it can force air out of the bellows until, as explained for Fig. 1, valve C reverses and chamber M² is connected with vacuum. Now atmospheric pressure in chamber D² will move piston F² toward the left until, as explained for Fig. 1, valve C returns to the position shown and the operation is repeated.

I claim:

1. A pneumatic pulsator comprising means providing a channel adapted for connection with a source of relatively low pneumatic pressure and a passage in which pneumatic pulsations are adapted to be produced, a member comprising valves adapted in one position to connect said passage with said channel and in the other position to connect said passage with a source of relatively high pneumatic pressure, an expandable and contractible fluid-containing chamber, a second fluid-containing chamber, means allowing only restricted flow of fluid between said chambers, each of said chambers being otherwise closed against admission or escape of air, a valve-actuator movable independently of said valves in one direction to first contract the first named chamber to cause fluid to flow therefrom into the other chamber and to then shift said valves from one position to the other and movable in the other direction independently of said valves to first expand the previously contracted chamber to thereby cause fluid to flow into it from the other chamber and to then reverse said valves, said valve actuator having pressure faces one of which is in fluid communication with said passage and which is therefore subjected to alternate high and low pressure by the movement of the valves into their opposite positions, the last named pressure face being of such area that, without changes of pressure on other working surfaces, the valve actuator moves in one direction or the other dependent upon whether the last named pressure face is subjected to high or low pneumatic pressure, each of said valves having its opposing faces open to high and low pressure respectively, opposing valve seats for each valve, the seats against which the low pressure sides of the valves contact being of greater diameter than those against which the high pressure sides of the valve contact, whereby the valves, when at either end of their stroke, are held at that end solely by fluid forces and offer resistance to movement by the actuator.

2. A pneumatic pulsator comprising means providing a channel adapted for connection with a source of relatively low pressure and two passages in which pneumatic pulsations are to be produced, a reciprocable member comprising valves adapted in one position to connect one of said passages with said channel and the other with a source of relatively high pressure and in the other position to reverse said connections, an expandable and contractible fluid-containing chamber, a second fluid-containing chamber, means allowing only restricted flow of fluid between said chambers, each of said chambers being otherwise closed against admission or escape of air, a valve-actuator movable independently of said valves in one direction to first contract the first named chamber to cause fluid to flow therefrom to the other chamber and to then shift said valves from one position to the other and movable in the other direction independently of said valves to first expand the previously contracted chamber to thereby cause fluid to flow into it from the other chamber and to then reverse said valves, said valve-actuator having pneumatic pressure faces one of which is connected with one of said two passages and which is therefore subjected alternately to high and low pneumatic pressures by the movement of the valves into their opposite positions, the last named pressure face being of such area that, without changes of pressure on other working surfaces, the valve actuator moves in one direction or the other dependent upon whether the last named pressure face is subjected to high or low pneumatic pressure, each of said valves having its opposing faces open to high and low pressure respectively, opposing valve seats for each valve, the seats against which the low pressure sides of the valves contact being of greater diameter than those against which the high pressure sides of the valve contact, whereby the valves, when at either end of their stroke, are held at that end solely by fluid forces and offer resistance to movement by the actuator.

3. A pneumatic pulsator as defined in claim 1 in which said fluid-containing chambers are bounded by three walls, namely, a rigid wall between and common to said chambers, a bellows forming the other wall of one chamber and a flexible wall forming the other wall of the other chamber.

4. A pneumatic pulsator as defined in claim 1 in which said valve-actuator comprises a piston having the specified pressure face that is subjected to alternate high and low pressures and having also an opposing pressure face of relatively small area communicating constantly with a source of relatively high pressure, a piston rod extending and slidably through said valve member, and means movable with the piston and piston rod adapted to contact with the valve member to effect its shift as specified.

5. A pneumatic pulsator as defined in claim 1

in which said valve-actuator comprises a piston having the specified pressure face that is subjected to alternate high and low pressures and having also an opposing face communicating constantly with a source of relatively high pressure and a spring tending to move said piston against said constant high pressure, the force of the spring sufficing to move the piston in one direction when the pressures on the opposing faces of the piston are balanced, but not sufficing to prevent movement of the piston in the opposite direction when the first named face of the piston is subjected to relatively low pressure.

6. A pneumatic pulsator as defined in claim 1 in which said valve-actuator comprises a piston having the specified pressure face that is subjected to alternate high and low pressures and having also an opposing pressure face of relatively small area communicating constantly with a source of relatively high pressure, the ratio between the diameters of the two opposing pressure faces being approximately $1:\sqrt{2}$.

7. A pneumatic pulsator comprising means providing a channel adapted for connection with a source of relatively low pneumatic pressure and a passage in which pneumatic pulsations are adapted to be produced, a member comprising valves adapted in one position to connect said passage with said channel and in the other position to connect said passage with a source of relatively high pneumatic pressure, an expandible and contractible fluid-containing chamber, a second fluid-containing chamber, means allowing only restricted flow of fluid between said chambers, each of said chambers being otherwise closed against admission or escape of air, a valve-actuator comprising two spaced apart diaphragms of different areas and a piston rod connected with both diaphragms, said valve actuator being movable independently of said valves in one direction to contract the first named chamber to cause fluid to flow therefrom into the other chamber and to then shift the valves from one position to the other and movable in the other direction independently of said valves to first expand the previously contracted chamber to thereby cause fluid to flow into it from the other chamber and to then reverse the valves, means to maintain the space between the two diaphragms of the valve actuator in connection with a source of low pressure, means adapted to maintain the outer face of the smaller diaphragm subject to a source of higher pressure, and means controlled by said valves in their specified movements to subject the outer face of the larger diaphragm to alternate higher and lower pressures, each of said valves having its opposing faces open to high and low pressure respectively, opposing valve seats for each valve, the seats against which the low pressure sides of the valves contact being of greater diameter than those against which the high pressure sides of the valve contact, whereby the valves, when at either end of their stroke, are held at that end solely by fluid forces and offer resistance to movement by the actuator.

8. A milking machine pulsator comprising a casing, a pneumatic braking device at one end of the casing, a valve actuator comprising a pneumatically controlled device at the other end of the casing and a rod connecting said devices, a double poppet valve, sleeved on said rod, between said devices and having a limited movement in opposite directions, the casing having two ports adapted for constant connection with a source of high pressure, one port between the valve and

said pneumatically controlled device and the other port between the valve and the braking device, the casing having also a low pressure port in constant connection with the space between the two members of the double valve and having also a passage adapted in the opposite positions of the valve to be connected alternately with one of said high pressure ports and said low pressure port, thereby producing pneumatic pulsations in said passage, means including a branch from said passage to said valve actuator whereby said pneumatic pulsations effect movement of the valve actuator in opposite directions, the range of movement of the valve actuator being so much greater than that of the valve that in the forepart of each of its movements said rod slides within the valve until the valve actuator engages the valve and thereafter shifts the valve from one end position to the other.

9. A milking machine pulsator comprising a casing, a pneumatic braking device at one end of the casing, a valve actuator comprising a pneumatically controlled device at the other end of the casing and a rod secured to and connecting said pneumatically controlled device and braking device, two spaced apart poppet valves and a hub carrying said valves and sleeved on said rod, thereby providing a double valve, inner and outer valve seats for each valve, the inner valve seats being of a substantially greater radius than the outer valve seats, there being high pressure ports in constant communication with the spaces outside the valves and a low pressure port in constant communication with the space between the valves whereby the opposing pneumatic pressures on the valves tend to hold them in either end position to which they are moved, there being also a pulsation passage between the two valve seats of one of the valves, and means including a branch from said passage to said valve actuator whereby the alternate high and low pressures in said pulsation passage, produced by reciprocation of the valves, effect movement of the valve actuator in opposite directions, the range of the movement of the valve actuator being so much greater than that of the valves that in the forepart of each movement of the valve actuator said rod slides within the valves until the valve actuator engages the valve and, after overcoming the pneumatic force tending to hold the valve from movement, shifts the valve to its opposite position.

10. A milking machine pulsator comprising an enclosing casing, a double poppet valve and a valve actuator, comprising a pneumatically controlled device and a rod, arranged and movable along a common axis; a valve-speed regulator comprising two air-containing chambers bounded by three walls, namely, a rigid wall between and common to said chambers and two walls one at least of which is flexible, there being fluid communication between said chambers of restricted and constant fluid flow capacity, said chambers being otherwise closed against admission or escape of air; said casing having a high pressure port, a low pressure port, and a pulsation passage; said valve having a limited movement along said axis into two opposite positions, in one of which it connects said pulsation passage with one of said ports and in the other of which it connects said pulsation passage with the other of said ports, means including a branch from said passage to said valve actuator whereby the alternate high and low pressures in said pulsation passage effect movement of the valve actuator along said axis in respectively opposite directions,

said rod being secured at one end to a flexible wall of the valve speed regulator, the valve being sleeved on said rod, the valve actuator, in its said movements, alternately expanding and contracting one of said chambers and in the forepart of each of said movements moving independently of said valve and for the remainder of its movement engaging the valve and shifting it from one to the other of its said positions.

11. A milking machine pulsator comprising a casing having therein ports adapted to communicate with sources of respectively high and low pneumatic pressure and a pulsation conduit, and enclosed within the casing at one end a pneumatic braking device and a valve actuator comprising a pneumatically controlled device at the other end of the casing and a piston rod connecting said two devices; a double poppet valve sleeved on said rod between the valve actuator and the braking device and movable into two opposite positions adapted to connect said ports respectively with said pulsation passage to produce therein alternate high and low pressures, means whereby the alternate high and low pressures in said pulsation conduit effect movement in opposite directions of the valve actuator and rod along the latter's axis against the action of said pneu-

matic braking device; said braking device comprising two air-containing chambers bounded by three walls, namely, a rigid wall between and common to said chambers, another wall constituting the second wall of one of said chambers and a bellows constituting the second wall of the other of said chambers, there being fluid communication between the two chambers of restricted and constant fluid flow capacity, said chambers being otherwise closed against admission or escape of air; the range of movement of the valve actuator being so much greater than that of the valve that in the forepart of each movement of the valve actuator the rod slides within the valve until the valve actuator engages the valve, after which continued movement of the valve actuator mechanically shifts the valve from one to the other of its opposite positions.

12. A milking machine pulsator as defined in claim 8 comprising means adapted to apply to the valve, when seated at either end stroke, differential pneumatic pressures tending to hold it seated and adapted, when unseated by the valve actuator, to equalize said pneumatic pressures and thereby allow the stroke of the valve to be quickly completed.

ERIK AUGUST FORSBERG.
